United States Patent Office

Des. 178,765
Patented Sept. 18, 1956

178,765

ILLUMINATED SLIDE VIEWER

Arthur H. Crapsey, Jr., Rochester, N. Y., assignor to Eastman Kodak Company, Rochester, N. Y., a corporation of New Jersey

Application September 19, 1955, Serial No. 37,983

Term of patent 14 years

(Cl. D61—1)

Fig. 1 is a perspective view of an illuminated slide viewer taken from the front and showing my new design; and

Fig. 2 is a perspective view taken from the rear of the illuminated slide viewer shown in Fig. 1.

I claim:

The ornamental design for an illuminated slide viewer, as shown.
